UNITED STATES PATENT OFFICE

2,438,853

BAROMETRIC FUZE

Hugh Charles Hebard, Greenford, England

Application February 23, 1945, Serial No. 579,384
In Great Britain May 31, 1943

5 Claims. (Cl. 102—70)

1

This invention relates to fuzes for aerial bombs, pyrotechnic devices and the like and to the kind wherin a barometric capsule is employed for the purpose of initiating ignition of the main fuze after the bomb or the like has fallen to a predetermined height above sea level, and has more particular reference to the device forming the subject of my prior application Serial No. 479,366, filed March 16, 1943, now Patent No. 2,422,548.

In devices of the kind indicated as previously constructed, the barometric capsule and its associated components has to be preset, for instance, at the factory, and could not conveniently be reset by the user. Owing to the fact that the sensitivity of the aneroid capsules which operate this type of fuze cannot readily be held within very close limits under manufacturing conditions, the provision of a scale for adjustment is difficult to make unless each fuze device is individually calibrated.

The object of the present invention is to provide an improved form of barometric fuze ignition means which is capable of adjustment by the user before use to vary the height at which fuze ignition takes place and wherin the capsules used may be of different sensitivity can be set by means of identical scales marked on the exterior of each fuze device.

According to the invention a barometric fuze device of the kind described is provided wherin the movement produced by the aneroid capsule or bellows is limited by an adjustable stop which is set for a range of operable firing conditions of the said capsule during assembly of the fuze and wherin the said stop can thereafter be adjusted by the user to set the said stop to a position which enables the fuze to be ignited at any desired altitude between the limits of said range.

According to the preferred form of the invention a barometric fuze device of the kind described is provided wherin the movement produced by an aneroid capsule or bellows is limited by an adjustable stop whose operable extreme positions are pre-set during assembly of the fuze to accord with the sensitivity of the particular capsule or bellows and whose position can be set thereafter between said operable positions by rotationally adjustable means to vary the extent of contraction permitted to said capsule in accordance with the altitude at which ignition of the fuze is to take place.

Reference will now be made to the accompanying drawings which illustrate by way of example a construction according to the invention and in which:

2

Fig. 1 is a sectional elevation.

Fig. 2 is a plan of Fig. 1 with the striker mechanism removed.

Fig. 3 is a detail perspective view showing a cam forming part of the adjusting mechanism.

Fig. 4 is a view similar to Fig. 1 but showing the parts in a different position and

Fig. 5 is an outside elevation.

In the construction illustrated, 10 indicates the casing of a barometric fuze device provided with striker mechanism having restraining and releasing means of the kind disclosed in said prior application Serial No. 479,366, whereby a spring-urged striker 19 is adapted to be released from its position of normal restraint by mechanical means actuated by movement of aneroid bellows 18 at a predetermined pressure, to enable the striker to be moved from the position shown in Figure 1 into that shown in Figure 4, when the striker actuates 20 a detonator to ignite a fuze.

This previously described construction forms no part of the present invention and need not, therefore, be described fully herein; but the scope of the present invention may be made clearer by 25 reference to certain features in common. The striker, for example, is held in the restrained position, Figure 1, by two sets of balls and movable sleeves. When the device is dropped from a height a wind vane 14 serves to withdraw the screw-threaded spindle 13 from the casing, as herein-after described, thereby removing an abutment from the lower base part of the bellows casing. Under the action of a spring 22, the bellows casing is moved downwardly as the spindle is withdrawn 30 until it makes contact with a stop member which sets the device in the armed position for the subsequent movement of the striker by contraction of the bellows to ignite the fuze. With the base part in contact with the said stop member, the striker is maintained in its inoperative restrained position until it is released from constraint by the contraction of the bellows at a predetermined atmospheric pressure as the device reaches a height corresponding thereto above sea level.

According to said prior application, the said adjustable stop member consists of an adjustable screw stop member 35. The present invention replaces the adjustable screw stop of said prior application by means which include a lever 2 (Fig. 1) 40 pivotally mounted at 3 in a block 4 mounted to slide over a fixed guide 5 in a direction radially of the device and adjustable towards or away from the axis thereof by means of a screw 6 whose head is accessible from the exterior of the casing 55 1, as shown in Fig. 5. A spring 16 is provided.

whose ends are fixed to the inner surfaces of the casing 1 and whose mid-portion bears against the block 4 to force it inwards as the screw 6 is slackened. The lever 2 has a tail portion 7 and both members are mounted upon a common pivot 3 carried by the radially movable block 4. The tail member 7 makes contact with the inclined upper edge of a circular cam 8 formed integral with a disc 9 adapted to be fixed centrally within the base 10 of the casing 1 by means of a nut 11 which engages a screw-threaded extension 12 on the disc, the arrangement enabling rotation of the base of the casing to vary the position of the cam to cause the inner end of the lever 2 to be lifted or lowered between the positions shown in Figs. 1 and 4.

The base part 10 of the casing is rotatable and has a scale of altitudes engraved on it (Fig. 5). The interior of the extension 12 is screw-threaded to engage the spindle 13 of a wind vane 14 which operates in the same manner as described in the said prior application, the spindle 13 passing through the lever 2 whose inner end is forked at 15 as shown in Fig. 2.

To ensure that the striker mechanism 17 shown in Figs. 1 and 4 will operate only at the exact predetermined height above sea level and avoid deviations due to the use of aneroid capsules 18 of varying sensitivity, the scale of altitudes on each device is accommodated to each capsule as a final operation in the production of the device. To this end two adjustments are made after the fuze has been assembled and before it is associated with a charge to be exploded or ignited. The first of the said adjustments is made at the zero setting of the scale by adjusting the length of the casing 1 of the fuze and, as this is the ground level setting, this adjustment can be made at atmospheric pressure. The adjustment is effected by using slotted holes for screws 21 which fix the outer casing 1 to the casting 23. The position of the zero mark of the scale on the rotatable member 10 is determined by the tail portion 7 of the stop lever 2. This tail piece rests on the cam 8 and lies at right angles to the axis of the fuze when the fuze is set at zero. That is, when this tail portion 7 is lifted by the rotatable cam 8 into the same horizontal plane as the axis of the member 3. The stop is thereafter set for the firing height desired by the user by the part 10 of the fuze being rotated to some point at the other end of the scale, say the point marked 10,000 ft., and the fuze is adjusted by rotating the screw 6 until the capsule causes the firing pin 19 to operate under a pressure equivalent to that at an altitude of 10,000 ft. This adjustment alters the ratio of the leverage between the stop lever 2 and its tail piece 7 which rests on the cam, and thus alters the position of the stop lever. Owing to the fact that the tail member 7 was at right angles to the axis of the fuze in the zero setting position the adjustment will not affect the zero adjustment so that two points on the scale will be correct. As the relation of the expansion of each individual capsule to the reduction in pressure is very nearly linear, the calibration of a fuze device set in the manner described will also be substantially correct at all other points on the scale.

In the operation of the device above described, the release of the bomb or the like from the aircraft causes the wind vane to rotate and withdraw the spindle 13 from contact with the bellows plate 20 until the continued rotation removes the spindle altogether from the extension 12 and the wind vane falls away. The removal of the spindle

allows a spring 22 acting on the casing to move the bellows as a whole downwards until its plate 20 makes contact with the stop lever 2 so that the device is in the armed condition as described in my aforesaid prior application. As the bomb or pyrotechnic device descends to regions of higher pressure, the bellows contracts and withdraws the release pin and enables the striker to operate. By employing a settable arrangement according to the present invention, which enables the sensitivity of any particular capsule to be taken into account, it is ensured that the striker will operate exactly at the predetermined height above sea level.

15 I claim:

1. A barometric fuze device comprising a casing embodying relatively adjustable sections, a firing pin and releasable restraining means therefor mounted in one of said sections, an aneroid capsule carrying means movable thereby for controlling said restraining means, a stop carried by the other casing section and settable by relative adjustment of the casing sections to predetermine the range of positions which the capsule may assume, a cam mounted rotatably in said other casing section and adjustable to vary the position of said stop, a scale and cooperating pointer for indicating the adjustments of the cam, and means for adjusting the stop to different positions corresponding to different indications on the scale.

2. A barometric fuze device comprising a spring actuated firing pin, means for releasably restraining said pin, an aneroid capsule, means operative in response to contraction of the capsule for releasing said restraining means, a stop adjustable to position the capsule bodily relatively to the firing pin to predetermine the range of operable positions of the capsule, said stop comprising a pivotally mounted lever having a member for adjusting it during assembly of the device, and manually settable means comprising a rotatable member adjustable to vary the inclination of said lever and thereby predetermine the position of the capsule at which its contraction will operate the restraining means to release the firing pin at any desired altitude.

3. A barometric fuze device comprising a spring-actuated firing pin, means for releasably restraining said pin, an aneroid capsule, means operative in response to contraction of the capsule for releasing said restraining means, a stop comprising a lever having a tail piece and adjustable to position the capsule bodily relatively to the firing pin to predetermine the range of operable positions of the capsule, manually settable means including a circular rotatable cam for adjusting said lever to predetermine the position of the capsule at which its contraction will operate the restraining means to release the firing pin, and a guide block on which said lever is pivotally mounted and adjustable radially of said cam, the tail piece of said lever resting on said cam and rotation of the latter adjusting the position of said lever.

4. A barometric fuze device comprising a spring-actuated firing pin, means for releasably restraining said pin, an aneroid capsule, means operative in response to contraction of the capsule for releasing said restraining means, a stop comprising a lever engageable with the capsule and adjustable to position the capsule bodily relatively to the firing pin to predetermine the range of operable positions of the capsule, said lever having a tail piece, manually settable means for adjusting said lever to predetermine the position

of the capsule at which its contraction will operate the restraining means to release the firing pin, said manually settable means comprising a cam with which the tail piece of said lever engages, and a block on which said lever is pivoted and adjustable radially of said cam to vary the ratio of leverage between said lever and tail piece and thereby vary the position of said lever at which it positions said capsule.

5. A barometric fuze device comprising a spring-actuated firing pin, means for releasably restraining said pin, an aneroid capsule, means operative in response to contraction of the capsule for releasing said restraining means, a stop comprising a lever engageable with the capsule and adjustable to position the capsule bodily relatively to the firing pin to predetermine the range of operable positions of the capsule, said lever having a tail piece, manually settable means comprising a rotatable cam engaged by the tail piece of said lever for adjusting the latter to predeter-

mine the position of the capsule at which its contraction will operate the restraining means to release the firing pin, a scale cooperative with the cam for indicating the positions into which the cam is rotated, and a block on which said lever is pivoted and adjustable radially of the cam.
